UNITED STATES PATENT OFFICE.

FRED S. ENGLISH, OF NEW LONDON, CONNECTICUT.

CUTTING AND CREAMING PRESS.

Application filed September 2, 1926. Serial No. 133,211.

My invention relates to presses for cutting and creasing sheets of paper, cardboard or other stock and the invention may be applied to a printing press which is used for cutting and creasing or to a press specially built for cutting and creasing. The invention is shown herein applied to a flat bed press though it will be apparent that my invention is not limited to this application.

On a bed and cylinder cutting and creasing press the sheets are cut by means of a form or die placed on the bed. A sheet of cardboard is fed to the cylinder and as it passes between the bed and cylinder it is cut into suitable sections to make boxes and it is creased on the lines on which bends or folds are to be made. It is customary to leave ties or tabs connecting various portions of the sheets connected where they would be otherwise entirely severed by the cutting rules, in order that sections of the sheet will be temporarily held together until the sheet is delivered from the press, the sheets being "stripped" after they are delivered from the press to remove or break these tabs or ties. It often happens that these tabs or ties are not strong enough to prevent portions of the cut and creased sheets from separating and the tabs or ties will sometimes fall upon the die or form and the present invention is adapted to remove the same from the die or form if they fall thereon. The present device embodies a member such as a brush for removing such parts from the die or form and in the full embodiment of the invention the brush is adapted to be operated so that it wipes the form or die either on the forward or backward stroke, or both, as may be required by the particular kind of job in hand. In addition I provide means for catching and holding such material as the brush may sweep from the form or die, in order that the same will not scatter upon other portions of the press or its mechanisms and so that the removed material may be conveniently taken from the press.

In the drawings forming part of this application,

Figure 1 is a side elevation of an ordinary cutting and creasing press with my present invention applied to it.

Figure 2 is an enlarged side elevation showing parts of the press and the sweeping device, with the bed near the end of its movement in one direction,

Figure 3 is a similar view showing the bed near the other extreme of its movement,

Figure 4 is a plan view of some of the parts shown in Figure 3, and

Figure 5 is a plan view of the parts shown in Figure 2.

In Figure 1 I have shown only such portions of a press as may be necessary to illustrate the application of my invention. Herein I have shown one of the side frames 15 of the press, the feed table 2, from which the sheets are fed, the impression cylinder 1, the sheet delivering device 7 for delivering the sheets from the cylinder, and the reciprocating bed 3, having a form or die 4 of cutting and creasing rules. In Figure 1 the impression cylinder is shown in position to take a sheet from the feed table 2, and as the cylinder revolves in the direction of the arrow, it carries the sheet around with it. At this time the bed 3 is moving toward the cylinder (in the direction of its arrow) and as the bed runs under the cylinder the die 4 cuts and creases the sheet on the cylinder. The sheet now passes on up with the cylinder at 80 and during this time cut portions are likely to fall out on the die, or if they do not fall entirely out they may come partly out, and these hanging portions are likely to hold onto some part of the die.

A brush 26 extends entirely across the press, over the path of the die and it is attached to arms 27 (one at each side of the press). These arms are fixed on the shaft 28 and this shaft is capable of being rocked 90 slightly by means of a lever 29, stud and roller 31, cam 32 and spring 30. This cam 32 can be attached to any shaft which makes one revolution per complete cycle of the press. I have shown it attached to the cross shaft 33. 95

It is evident that this cam can be timed by altering its angular position on the shaft 33 so that the brush 26 will sweep the die with the bed moving in either direction, or by the simple expedient of slipping the cam 100 endwise on the shaft the lever 29 can be made to come down against the stop 40 and remain there, thus sweeping the die during both strokes of the bed.

At 34 and 35 I have shown trays attached to opposite ends of the bed to collect the sweepings from the operations of the brush. In Figures 3 and 4 I have shown a fixed brush which will always sweep in both directions of movement of the bed. Here the 110

- brush is designated 36 and it is attached to a bar 38 extending across the press and fixed on stationary brackets 37 attached to the frame 15 of the press. It is best that the brush should have a slight adjustment up and down. I have provided for this by means of a slot 39 for the stud and roll in the lever, or it may be done by underlying between the brush and the supporting brackets or levers.
- From the above it will be apparent that the brush may be arranged to sweep the die in either direction of movement of the bed or it may be set to sweep the die in both directions of movement of the bed. As foreign material is swept from the die by the brush it is deposited in the tray at one end of the bed or when the brush is sweeping the die in both directions the foreign matter may be swept into both trays alternately as the bed moves back and forth. From these trays the refuse may be cleared out when the press is stopped. With this arrangement the foreign substances are collected instead of being allowed to scatter through the press and clog the working mechanisms. The die can be kept clean at all times and this will protect the die from injury which might otherwise occur if the cuttings were allowed to remain. These cuttings or foreign material, even if they should not cause injury to the die would, if allowed to remain on the die, affect the operation of the rules of the die on sheets which are fed through the press, resulting in defective sheets, being delivered from the press.
- Having described my invention what I claim is:—
1. The combination of a press for cutting and creasing stock including a cutting die, and impression cylinder, and means adjacent the path of said die for brushing the surface thereof.
  2. The combination of a press for cutting and creasing stock including a cutting die, and impression cylinder, means adjacent the die for brushing the surface thereof, and means for adjusting said brush means in relation to said die.
  3. The combination of a press for cutting and creasing stock including a cutting die, an impression cylinder, and means movable toward and from the die and adapted to brush the surface thereof.
  4. The combination of a press for cutting and creasing stock including an impression cylinder, a movable cutting die, means movable toward and from the cutting die adapted to brush the surface thereof, and means for automatically moving said brushing means into and out of action upon said die.
  5. The combination of a press for cutting and creasing stock including an impression cylinder and a reciprocating bed, and cutting die carried by the bed, means movable toward and from the die, adapted to brush the surface thereof, and means for automatically placing said brushing means into operative position during the movement of said bed in one direction and for placing said brushing means in an inoperative position during the reverse movement of the bed.
  6. The combination of a press for cutting and creasing stock including a cylinder, a cutting die, means for brushing said die, and cam and lever means for automatically throwing said brushing device into and out of operation on said die.
  7. The combination of a press for cutting and creasing stock including an impression cylinder, a cutting die, means for brushing said die and automatic means for placing said brushing means into and out of operative relation to said die, said automatic means being adjustable whereby the timing of the operation of said brushing means may be varied.
  8. The combination of a press for cutting and creasing stock including an impression cylinder, a movable bed, and a refuse collecting tray attached to and movable with the bed.
  9. The combination of a press for cutting and creasing stock including an impression cylinder, a removable bed, brushing means adapted to wipe the surface of a die carried by said bed, and a refuse collecting tray movable with the bed and adapted to receive refuse dislodged by said brushing means.
  10. The combination of a press for cutting and creasing stock including an impression cylinder, a reciprocating bed, brushing means adapted to wipe the surface of a die carried by said bed, and a refuse collecting tray at each end of said bed, adapted to receive refuse dislodged by said brushing means.
  11. The combination of a press for cutting and creasing stock including an impression cylinder, a reciprocating bed carrying a die, a brush arranged to wipe the surface of the die as the bed reciprocates in relation to the brush and a tray carried by said bed and arranged adjacent the point at which the brush leaves contact with the surface of the die, for receiving material brushed from the die.

Signed at the city and county of New London, State of Connecticut, this 18th day of August, 1926.

FRED S. ENGLISH.
